UNITED STATES PATENT OFFICE.

ROY P. REYNOLDS, OF HARRISONVILLE, MISSOURI.

ADJUSTABLE TAPPET-WRENCH.

1,385,228.

Specification of Letters Patent. Patented July 19, 1921.

Application filed November 29, 1920. Serial No. 427,147.

To all whom it may concern:

Be it known that I, ROY P. REYNOLDS, a citizen of the United States, and resident of Harrisonville, county of Cass, State of Missouri, have invented a certain new and useful Improvement in Adjustable Tappet-Wrenches, of which the following is a complete specification.

This invention relates to a tool for use in adjusting the lift of tappet valves of explosive engines, and has for its object to produce a device of this character by which the tappet stem and the plunger may be immovably held against turning and including provision for effecting a relatively fine adjustment of the tappet stem and maintaining such adjustment during the operation of tightening the lock nut found in connection therewith.

Another object is to produce a device of this character of simple, strong, durable, efficient and inexpensive construction: and in order that it may be fully understood, reference is to be had to the accompanying drawing, in which:

Figure 1 is a perspective view of the device as it will appear when in use in connection with the adjustment of a lock nut;

Fig. 2 is a section on the line II—II of Fig. 1, to more clearly illustrate the ball and socket and swivel connections of one of the members of the device;

Fig. 3 is a section on the line III—III of Fig. 2; and

Fig. 4 is a section on the line IV—IV of Fig. 3.

In the said drawing, where like reference characters identify corresponding parts in all of the figures, 1 and 2 constitute the handles of the device, the former being bifurcated at one of its ends as at 3, for the reception between the ears thus formed of the arm 2, and the two members are secured in pivotal relation by means of a pivot pin 4.

At its opposite end the handle 1 is provided with an L-shaped jaw 5, and pivoted thereto by means of cross-links 6 is a similar, but movable jaw 7 of L-shape to correspond with the jaw 5, the shank of said movable jaw being provided with a threaded perforation for the reception of a set screw 8 provided with a thumb portion 9 at its outer end, the opposite end being adapted to bear against the side of the handle 1. By this arrangement the movable jaw, in combination with the immovable jaw, may be adjust-

ed to accommodate the squared end of a tappet plunger 10 of an engine, not shown.

The handle 2 is provided with a pair of extensions 11 adapted to receive, for pivotal action between them a wrench 12 mounted on a pivot pin 13. The wrench is formed of two members, a movable jaw 14 and a substantially fixed jaw 15, having tongue and groove relation, the former being provided with opposite grooves 16 and the latter bearing a pair of spaced tongues 17 for slidable interlocking engagement with the grooves 16. The face of the movable jaw being threaded as at 18 for the reception of a thumb nut 19 mounted on the jaw 15 within an opening 20 thereof.

Mounted in the free end of the shank of the immovable jaw 15 with a ball and socket connection 21 is a set screw 22 provided with a thumb portion 23. The set screw is threaded through a swivel nut 24 mounted between the extensions 11 of handle 2, and is free for pivotal action on its trunnions 25. It will be understood that after the jaws 5 and 6 are set to firmly grip the squared end of the plunger 10, that the jaws of the wrench 12 will be adjusted to grip the squared head 26 on the upper end of a threaded tappet stem 27, which is screwed into the plunger 10, as customary, and that in order to secure a final and accurate adjustment and firmly hold the plunger and tappet in their relative positions while the lock nut 28 of the tappet is being adjusted, the set screw 22 will be turned to more securely hold the tappet from movement by leverage action.

A recapitulation of the operation of the invention is believed to be unnecessary, other than to state that it will be understood that the adjustments of the lock nut must be carried out through the use of an ordinary wrench or other tool, and that the ball and socket and swivel connection of set screw 22 is provided in order that said screw, when turned may effect the final adjustment of the tappet and retain it in adjusted position, while the tool as a whole operates to maintain the parts in finely adjusted relation while the lock nut 28 is tightened by the use of a separate tool.

From the above description it will be apparent that I have produced a device of the character set forth which possesses all the features of advantage named, and while I have described and illustrated the pre-

ferred embodiment of the same, I reserve the right to all changes properly falling within the spirit and scope of the appended claims.

5. What I claim is:—

1. In a tool of the character described, a pair of handles bearing a pivoted relation to each other, one of said handles being provided at its outer end with a pair of jaws, 10 and a wrench carried by the companion handle, and means carried by said second handle for operating the wrench, said handles being so proportioned that the wrench and jaws may be brought simultaneously into operative engagement with parts working about the same axis.
2. In a tool of the character described, a pair of handles bearing a pivoted relation to each other, one of said handles being provided at its outer end with a pair of jaws; the companion handle being provided with a pair of extensions, a wrench adapted to have a pivotal connection with said extensions; and means separate from said pivotal point for imparting pivotal action to the wrench and retaining it in any predetermined position of adjustment.
3. In a tool of the character described, a pair of handles bearing a pivoted relation to each other, one of said handles being provided at its outer end with an immovable jaw having a movable jaw pivoted thereto,

and means for locking the movable jaw against outward movement; the companion handle being provided with a wrench at its 35 outer end and being so proportioned that its wrench may be brought simultaneously with said jaws into operative engagement with parts working about the same axis.

4. In a tool of the character described, a 40 pair of handles bearing a pivoted relation to each other, one of said handles being provided at its outer end with an immovable jaw having a movable jaw pivoted thereto, and means for locking the movable jaw 45 against outward movement; the companion handle being provided with a wrench at its outer end, and means carried by said handle for operating said wrench.

5. In a tappet adjusting tool, a pair of 50 handles bearing a pivoted relation to each other, one of said handles being formed with an immovable jaw at its outer end having a movable jaw pivoted thereto, and a set screw threaded in one end of the movable jaw and 55 adapted to abut against the inner side of the handle; the companion handle being provided with a pair of extensions, a wrench pivoted between said extension, means having a ball and socket connection with said 60 wrench for operating the latter.

In witness whereof I affix my signature.

ROY P. REYNOLDS.
